UNITED STATES PATENT OFFICE.

WILLIAM J. BASTIAN AND FRANK GRANITZ, OF CHICAGO, ILLINOIS, ASSIGNORS TO AMERICAN CUTLERY COMPANY, OF CHICAGO, ILLINOIS, A CORPORATION OF ILLINOIS.

GRINDING-MACHINE.

No. 921,343.

Specification of Letters Patent.

Patented May 11, 1909.

Application filed December 14, 1908. Serial No. 467,411.

To all whom it may concern:

Be it known that we, WILLIAM J. BASTIAN and FRANK GRANITZ, citizens of the United States, residing at Chicago, in the county of 5 Cook and State of Illinois, have invented a new and useful Improvement in Grinding-Machines, of which the following is a specification.

Our invention relates to improvements in 10 the class of machines for grinding cutlery, such as knife-blades, or the like, in which a reciprocating work-carrier, or holder, is employed for moving the article to be ground against the grinding surface of a grinding- 15 wheel.

The principal objects of our invention are 20 to provide a machine of the character referred to which will be positive in operation, which will be of such a construction as not to be rendered impaired for accurate work by long continued use; and, in general, to provide a machine which will serve to perform, to the fullest degree of satisfaction, the work required of machines of this class.

25 In the accompanying drawings we have illustrated our invention as embodied in a machine in which the grinding is performed during the return movement only of the work-carrier, in which—

30 Figure 1 is a plan view of a machine constructed in accordance with our invention. Fig. 2 is a section taken at the line 2 on Fig. 1 and viewed in the direction of the arrow. Fig. 3 is a section taken at the line 3 on Fig. 35 1 and viewed in the direction of the arrow, this view being enlarged and illustrating the position of the gear-mechanism for actuating the work-carrier and the operating lever for said mechanism, when the operating lever is 40 in the position for moving the work-carrier toward the grinding-wheel. Fig. 4 is a section taken at the line 4 on Fig. 3 and viewed in the direction of the arrow. Fig. 5 is a view like that of Fig. 3, showing the position 45 of the gear-mechanism and the operating handle therefor when said handle is moved to a position for reversing the movement of the work-carrier. Fig. 6 is a section taken 50 at the irregular line on Fig. 5 and viewed in the direction of the arrow, this view illustrating the gears in top plan. Fig. 7 is a section taken at the irregular line 7 on Fig. 5 and viewed in the direction of the arrow. Fig. 8 is a top plan view of the oscillating bed 55 of the machine, with the coöperating carriage

therefor removed. Fig. 9 is a bottom plan view of the reciprocating work-carrier which, in the operation of the machine, reciprocates upon the bed illustrated in Fig. 8. Fig. 10 is an enlarged section taken at the line 10 on 60 Fig. 8 and viewed in the direction of the arrow. Fig. 11 is a section taken at the line 11 on Fig. 1, the parts illustrated in this figure being shown in normal position. Fig. 12 is a section taken at the line 12 on Fig. 1 65 and viewed in the direction of the arrow, with the arms for engaging with the lever for controlling the position of the gears, in side elevation, the parts illustrated in this figure being shown in the positions they assume when the work-holder has reached the limit of its forward movement; and Fig. 13 is a view like that of Fig. 12 showing the position 70 the parts assume preparatory to the initial movement of the work-holder in returning to normal position.

The frame of the machine is illustrated at 14, the upper portion thereof being formed with an upright conduit 15 having an opening 15^a in its lower end through which water, 80 which may be applied to the grinding-wheel in any desirable well-known manner, as through the pipe 16^a, discharges, the grinding-wheel of the machine being illustrated at 16 and extending into the top portion of 85 the conduit. The grinding-wheel illustrated is of the well-known annular type provided with a tapering grinding surface 17, this wheel being mounted upon a shaft 18 carrying loose and fixed pulleys 19 and 20, respectively, located on the shaft intermediate bearings 21 and 22 for the shaft 18, these bearings being carried by the frame of the machine, as hereinafter more fully described. Extending from the conduit portion 15 of the 90 frame beyond the grinding-wheel 17 is a frame-extension 23, this extension being of general rectangular form and recessed as shown. A bracket 24 having a flat upper surface and alining with the upper surface of 100 the extension 23 extends forwardly of this extension, and resting upon the upper surface of the latter and this bracket is a bed 25 of general rectangular form, pivoted at its forward end to the forward end of the 105 bracket 24 as indicated at 26, and connected at its opposite end at a lug 27 with one end of a spiral spring 28, this spring having adjustable connection at its other end with a lug 29 on the extension 23, this spring-connec- 110

tion tending to swing the bed on its pivot 26 away from the grinding-wheel. The upper side of the bed 25 carries two parallel longitudinally extending tongues 30, 30, and reciprocably mounted upon the bed 25 is a work-carrier, or holder, 31, grooves 32, 32 in the under side of which receive the tongues 30 for the purpose of guiding the carrier in its reciprocations hereinafter described.

10 The side of the carrier 31 adjacent to the grinding-wheel carries a stud 34 and a hook 35 adapted to releasably retain a knife on the carrier for moving it into contact with the grinding surface of the wheel when the carrier is reciprocated.

15 The means for reciprocating the carrier 31 upon the bed 25 for moving the work-holder across the grinding surface of the wheel 16 are as follows: Secured to the extension 23, 20 as by brackets 36, is a gear-casing 37 formed of two separable members 38 and 39. Located in this casing is a drive-pinion 40 fixed on one end of a drive-shaft 41 carrying a drive-pulley 42 and journaled in bearings 43 and 44 secured to the frame of the machine, it being designed that this shaft be driven from any suitable source of power. Meshing with the pion 40 is a gear 45 journaled on a stub-shaft 46 extending from a side of the 30 casing. The gear 45 has a sleeve-extension 47 to which a pion 48 is keyed as represented at 49. Meshing with the pion 48 is a gear 50 journaled on a shaft 51 fixed at one end in one side of the casing and at its 35 other end in a boss of larger diameter extending inwardly from the opposite side of the casing. The gear 50 has a sleeve-extension 52 on which a gear 53 is fixed as by the key 54. Journaled on the shaft 51 is an oscillating plate 55, this plate carrying two stub-shafts 56 and 57 on which non-aligning gears 58 and 59 are respectively journaled. The 40 gear 59 has fixed to it a pion 60, meshing with the gear 58, the gears 58 and 59 being so disposed on the plate 55 with relation to the pion 53 as to cause the pion 53 to constantly mesh with the gear 58 but be out of mesh with the gear 59 at all times. It is thus manifest that the gear 59 when the 45 pion 53 is rotated will rotate in a direction opposite to that of the gear 58, and furthermore the speed of rotation of the gear 59 will be greater than that of the gear 58. Journaled in the upper portion of the gear-casing 50 is a shaft 61 having fixed thereon a gear 62 and a pion 63, so disposed with relation to the gears 58 and 59 that when the plate 55 occupies the position represented in Fig. 3, the gear 59 will mesh with the pion 63 and 55 the gear 58 will be out of mesh with the gear 62; and when this plate is in the position represented in Fig. 5 the gear 58 will mesh with the gear 62 and the gear 59 will be out of mesh with the gear 63. The protruding end 60 of the shaft 61 carries a yoke-extension 64, in

the arms of which a pin 65 is fixed, and journaled on this pin is a spherical shaped member 66 which likewise is journaled on an intersecting pin 67 fastened in the arms of a yoke 68 extending from the outer end of a shaft 69 journaled in a bearing 70 fastened to the under side of the bed 25 and extending through an opening 71 in the extension 23, the shaft 69 being free to move slightly in the bearing 70 longitudinally thereof. The inner 75 end of the shaft 69 carries a pion 72 which projects upwardly through a slot 73 in the bed 25 and engages with a rack 74 on the under side of the work-carrier 31. The rack 74 which extends longitudinally of the carrier is located in a longitudinally-extending recess 75 therein, this rack containing near its opposite ends two longitudinally elongated slots 76, 76 through which the shanks 77 of the headed screws 78 fastened in the carrier 80 31 extend, the heads 79 of these screws being of a diameter exceeding the width of the slots 76, whereby the depending rack 74 is held in the recess 75, and the shanks 77 of these screws being of such a size as to permit 90 the rack to have limited independent longitudinal movement relative to the carrier 31. The forward end of the rack 74 carries an upright pin 80 which extends upwardly through an elongated slot 81 in the carrier 31, the 95 upper extremity of this pin affording journal connection for one end of a bell-crank lever 82, at an elongated slot 83 therein, the lever 82 being fulcrumed as represented at 84 on the upper surface of the carrier 31. As a 100 means for protecting the bearings of the lever 82, we prefer to provide a cap 85 which is secured upon the carrier as represented, the outer end of the bell-crank 82 extending through a slot 86 in a side of the cap and 105 carrying a roller 87 adapted to constantly bear, under the influence of the spring 28, against the surface 88 of a guide 89 secured to the frame of the machine on brackets 90.

110 The machine in its operation is caused to carry the work forwardly toward the grinding-wheel, but out of contact therewith, and to perform the grinding upon the return movement only of the work-carrier, it being designed that the machine be automatic in 115 the respect that when once started in operation the movement of the carrier 31 will be automatically reversed to cause said carrier to perform a complete reciprocation, the means for accomplishing this operation being as follows: Journaled on a stud 91 fastened in a side of the gear-casing 37 is a lever 92, the lower end of which is connected with one end of a coil spring 93 carried by an extension 94 secured to the casing 37. 125 Extending forwardly from the lever 92, at a point adjacent to the pivot 91, is an arm 95, the forward extremity of which contains an elongated slot 96 into which a pin 97 carried by the plate 55 extends. The upper end of 130

the lever 92 is in the form of a handle 98 carrying a lever 99 fulcrumed between its ends as indicated at 100 to a stud 101 extending laterally from the lever 92, it being designed 5 that the lower end of the lever 99 be normally spring-pressed toward the lever 92 through the medium of a spring 102 to ride against the lateral edge-portion of a U-shaped member 103 secured to the upper side of 10 the casing 37, as indicated at 104, and containing two spaced recesses 105, 106 forming shoulders adapted to be alternately engaged by the lower end of the lever 99 for releasably holding the lever 92 in different 15 positions against the tension of the spring 93 for the purpose hereinafter expressed.

Assuming the machine to be in the normal position illustrated in Fig. 1 and the drive-shaft 41 and shaft 18 to be constantly rotated by any suitable source of power, the operation, in so far as the machine has been described, is as follows: The operator after applying a knife, or any other article to be ground, to the pin 34 and hook 35 of the 25 work-carrier 31, draws back the lever 92 against the action of its spring 93 until the lower end of the lever 99 engages with the shoulder of the recess 105 by reason of the action of the spring 101, as clearly represented 30 in Figs. 3 and 4. Thus shifting the lever 92 causes the plate 55, by reason of its connection with the rigid arm 95, to be oscillated to the position illustrated in Fig. 3, in which position the gear 58 is out of mesh with the 35 gear 62 and the gear 59 meshes with the pinion 63. From the foregoing description of the relation of the gears to the drive-shaft 41 and to the pinion 72, it will be understood that the constant rotation of the pinion 40 40 produces a continuous drive of the gears 58 and 59, and the gear 59 being in mesh with the pinion 63 thereby drives the pinion 72, when the plate 55 is moved to the position hereinbefore referred to as illustrated in Fig. 45 3. The rack 74 and lever 82 being normally in the positions illustrated in Figs. 1 and 11, the initial rotation of the pinion 72 to the right in Fig. 11 causes the rack to slide in the recess containing it in the carrier 31 to a position 50 in which the rear end-walls of its slots 76 engage with the shanks 77 of the screws 78. This initial movement of the pinion 72 causes the lever 82 to swing upon its pivot 84, thereby moving the arm thereof carrying 55 the roller 87 toward the front of the machine, with the result of permitting the spring 28 to swing the bed 25 at its free end to the right in Fig. 1, thus swinging the work-carrier 33 to a position in which it is out of alignment with 60 the grinding surface of the wheel 16. Continued movement of the pinion 72, by reason of its engagement with the teeth of the rack 74, and by reason of the engagement of the rear end-walls of the slots 76 with the screws 65 78, causes the carrier 31 to be moved toward

the grinding-wheel, it being understood that in this construction the article to be ground during the forward movement of the carrier does not contact with the grinding surface of the wheel 16. The carrier continues in 70 this movement until an arm 107 adjustably connected with the carrier 31 and extending laterally therefrom engages at a cam surface 108 thereon with the upper end portion of the lever 99, this engagement causing the lower 75 end of the lever 99 to be withdrawn from engagement with the shoulder 105 thereby permitting the lever 92 to turn to the position illustrated in Fig. 5 under the action of its spring 93, in which the lever 99 engages at 80 its lower end with the shoulder of the recess 106. As hereinbefore explained, it is designed that the article be moved against the grinding surface of the wheel 16 upon the return movement only of the carrier 25, and 85 this result is accomplished in the following manner: The throwing of the lever 92 to the position illustrated in Fig. 5 swings the plate 55 to a position in which the gear 59 is out of mesh with the gear 63 and in which the 90 gear 58 meshes with the gear 62. The result of the engagement of these gears as described is that of causing the pinion 72 to be rotated in the reverse direction, but much more slowly than where it is rotated through 95 the engagement of the pinion 63 with the gear 59, as is readily apparent from the foregoing description of the gear connections. It is thus manifest that before the carrier 31 commences its return movement, which will 100 necessarily be slower than its forward movement in carrying the work-carrier toward the grinding-wheel, the rack 74 must first be moved until the forward end-walls of the slots 76 engage with the shanks 77 of the 105 screws 78, the movement of the rack 74 to this position occurring during the initial rotation of the pinion 72 immediately following the swinging of the plate 55 from the position illustrated in Fig. 3 to that illustrated in Fig. 5. During the movement of the rack 74 independent of the carrier 31 as just described, the lever 82 is swung to the position opposed to that hereinbefore described in which the outer roller-equipped 110 extremity of the latter is moved forwardly, thereby forcing the bed 25 and the work-holder 33 toward the grinding-wheel against the tension of the spring 28. As soon as the rack 74 has completed its movement independent of the carrier 31, its engagement with the screws 78 operates, under the continued rotation of the pinion 72, to return the carrier 31 to normal position, during 115 which movement the article is pressed against the grinding-wheel and is ground. The provision of the gears on the plate 55 whereby oscillation of the latter serves not only to reverse the direction of rotation of the shaft 61 and therefore the pinion 72, 120

125 65 78, causes the carrier 31 to be moved toward

but also to provide a greater speed of rotation of the shaft in one direction, serves as a very simple form of differential gear transmission, though it will be understood that 5 the invention is not limited to this particular form.

It will be apparent that the turning of the lever 82 to the position just described, in which it forces the carrier 31 toward the 10 grinding-wheel, operates against the tension of the spring 28, and that, unless some positive means for holding the carrier against movement on the bed 25 is provided during such turning of the lever, the bed might begin 15 its return movement immediately upon the reversal of the machine as described before the lever 82 has forced the bed toward the grinding-wheel. To prevent such an occurrence, we provide stop mechanism of 20 which the following is a description: Pivoted at one end, as indicated at 109, on the side of the carrier 31 adjacent to the guide 89 is a catch 110 normally downwardly pressed by a coil spring 111, the free end of this catch 25 carrying a shoulder 112; and similarly pivoted between its ends, as indicated at 113, is a lever 114 having a shouldered portion 115 engaging with the free end of the catch 110 as represented in Figs. 12 and 13, the opposite 30 end of the lever 114 having a cam surface 115^a which normally projects into the path of movement of the outer extremity of the bell-crank 82. Adjustably secured on a side of the bed 25 and adjacent to the levers 35 110 and 114, is a block 116, which extends into the path of the free end of the lever 110 during the forward movement of the carrier 31. The block 116 should be so positioned that the shoulder 112 will be caused, after riding 40 over the top of this block during the forward movement of the carrier, to be forced by the spring 111 into engagement with the forward end of the block 116, and thus as soon as the lever 92 has been automatically 45 moved to the reversing position illustrated in Fig. 5 for moving the bell-crank 82 and returning the carrier 31, it will engage with this block and prevent movement of the carrier while the rack is moving relative thereto. 50 The cam surface 115 is so disposed as to cause the adjacent edge of the lever 82 to ride upon it and raise the shoulder 112 to the position illustrated in Fig. 13 in which it clears the block 116 at the conclusion of the 55 movement of the rack 74 relative to the carrier 31. Thus the positive turning of the lever 82 to force the carrier 31 toward the grinding-wheel before the carrier commences its return movement is insured. 60 The carrier 31 continues on its return movement until an arm 117 adjustably connected with the carrier 31 engages the lever 98 and moves it to the intermediate position illustrated in Fig. 1, in which neither of the 65 gears 58 and 59 mesh with the gears 62 and

pinion 63 respectively, and thus no power is communicated to the pinion 72, and the machine stops.

The oscillation of the bed 25 and carrier 31 causes the rack to be moved longitudinally 70 of the pinion 72 and the shaft 69 to change to a slight degree its angular relation to the shaft 61, the sliding of the shaft 69 with relation to the bed and carrier being provided for by the journal connection of this shaft 75 with the bed as hereinbefore described, and the changing of the inclination of the shaft 69 to the shaft 61 being compensated for by the sliding, universal joint between these shafts hereinbefore clearly set forth. 80

The material of which the grinding-wheel is usually composed is of such a character as to cause it to wear away more or less rapidly, and thus it is desirable that the wheel be so mounted on the frame of the machine as to 85 permit it to be readily fed toward the path of movement of the article to be ground as this wear takes place. To insure the stability and positiveness of operation required of this feature of a machine, we provide the 90 following described construction: Extending parallel with the shaft 18 and on opposite sides below it, are two rods 118 of angular shape in cross-section, and embracing these rods are four bearings 119 to which the bearings 21 and 22, hereinbefore referred to as supporting the shaft 18, are secured, whereby movement of the bearings 119 upon the rods 118 likewise moves the shaft 18 and the grinding-wheel carried thereby in a longitudinal direction. The pair of bearings 119 at the end of the machine are connected by a 100 web 120 having a threaded bore 121 into which the threaded end 122 of a shaft 123 journaled in a cross-bar 124 rigid with the 105 rods 118, is journaled. The outer end of the shaft 123 carries a pinion 124^a which meshes with a pinion 125 carried on a shaft 126 journaled in bearings 127 on the frame of the machine and carries at its opposite end a 110 hand-wheel 128. It will be manifest from the foregoing description of this part of the machine that the operator may, by turning the wheel 128, move the shaft 18 and wheel 16 upon the rods 118, as adjustment of the 115 wheel with relation to the work-holder is required.

The water fed to the interior of the wheel 16 through the pipe 16^a is caused by the rotation of the wheel to be thrown outwardly 120 upon its grinding-surface and against the hood covering the wheel, and to prevent the discharge of water through the opening in the hood for the work-carrier upon the latter and the carriage we provide means for re- 125 turning the water toward the wheel, the form preferred comprising two horizontally-extending flanges having curved upper surfaces extending inwardly from the hood, as represented, a slight distance above the 130

plane of movement of the work-holder. The water discharged toward the hood thus impinges against these flanges and is deflected toward the wheel, thereby preventing water 5 from being discharged upon the holder or carrier.

It will be noted that, by adjustably connecting the arms 107 and 117 with the carrier 31 and adjustably mounting the block 116 10 upon the bed 25, the extent of the forward and return movements of the carrier 31 may be regulated for the grinding of articles of different lengths.

From the foregoing description of the machine it is manifest that the parts thereof are 15 so constructed, and coöperate with each other in such a manner, that the operation of the machine is rendered positive and impairment of the machine, to perform accurate 20 work, by long continued use is avoided.

What we claim as new, and desire to secure by Letters Patent, is—

1. In a grinding-machine, the combination with its frame and a grinding-wheel 25 journaled thereon, of a reciprocatory work-carrier, a drive-shaft, and a movable member carrying gears operatively connected with said drive-shaft and constructed and arranged to drive said carrier in opposite directions when said member is moved.

2. In a grinding-machine, the combination with its frame and a grinding-wheel journaled thereon, of a reciprocatory work-carrier, a drive-shaft, a rack on said carrier, 35 and a movable member carrying gears operatively connected with said drive-shaft and rack for driving the carrier in opposite directions when said member is moved.

3. In a grinding-machine, the combination with its frame and a grinding-wheel journaled thereon, of a reciprocatory work-carrier, a drive-shaft, a movable member carrying gears operatively connected with 40 said drive-shaft and constructed and arranged to drive said carrier in opposite directions when said member is shifted, and manually-operated means for moving said member, for the purpose set forth.

4. In a grinding-machine, the combination with its frame and a grinding-wheel journaled thereon, of a reciprocatory work-carrier, a rack operatively connected with the work-carrier, a drive-shaft, a pinion engaging with said rack, a gear movable with 55 said pinion, a pinion on said drive-shaft, and a movable member carrying gears and constructed and arranged to be moved to operatively and alternately connect the gears carried thereby with the pinion on said drive-shaft and with said first-named gear, for the purpose set forth.

5. In a grinding-machine, the combination with its frame and a grinding-wheel journaled thereon, of a reciprocatory work-carrier, a rack operatively connected with 60

the work-carrier, a drive-shaft carrying a pinion, a pinion engaging said rack, a gear movable with said pinion, a movable member carrying gears and constructed and arranged to be moved to operatively and alternately connect the gears carried thereby with the pinion on said shaft and with said first-named gear, and manually-operated means for moving said member, for the purpose set forth. 70

6. In a grinding-machine, the combination with its frame and a grinding-wheel journaled thereon, of a reciprocatory work-carrier, a drive-shaft, a movable member carrying gears operatively connected with 80 said drive-shaft and constructed and arranged to drive said carrier in opposite directions when said member is shifted, and a lever operatively connected with said member, for the purpose set forth. 85

7. In a grinding-machine, the combination with its frame and a grinding-wheel journaled thereon, of a reciprocatory work-carrier, a drive-shaft, a movable member carrying gears operatively connected with 90 said drive-shaft and constructed and arranged to drive said carrier in opposite directions when said member is shifted, a lever operatively connected with said member for shifting the latter, and means operated by 95 the movement of said work-carrier for actuating the lever, for the purpose set forth.

8. In a grinding-machine, the combination with its frame and a grinding-wheel journaled thereon, of a reciprocatory work-carrier, a drive-shaft, a movable member carrying gears operatively connected with 100 said drive-shaft and constructed and arranged to drive said carrier in opposite directions when said member is moved, and 105 means operated by the movement of said carrier for shifting said member, for the purpose set forth.

9. In a grinding-machine, the combination with its frame and a grinding-wheel journaled thereon, of a reciprocatory work-carrier, a drive-shaft, a movable member carrying gears operatively connected with 110 said drive-shaft and constructed and arranged to drive said carrier in opposite directions, when said member is shifted, a spring-controlled lever operatively connected with said member, means for releasably holding said lever in position against the tension of its spring in which the gears operate to move 115 the holder in one direction, and means operated by the movement of said carrier for releasing said handle to shift said member and reverse the movement of said work-carrier, for the purpose set forth. 120

10. In a grinding-machine, the combination with its frame and a grinding-wheel journaled thereon, of a reciprocatory work-carrier, a gear and a pinion operatively connected with said carrier in a manner to move 130

- the latter during the rotation of said gear and pinion, a drive-shaft, and a movable member carrying gears and a pinion rigid with one of said gears and meshing with the other of the 5 gears carried by said member, one of the gears carried on said member being operatively connected with said drive-shaft, said movable member and its gears being so constructed and arranged as to cause the pinion 10 and gear meshing with it on the movable member to alternately engage with said first-named pinion and gear, respectively, when the position of said movable member is shifted, for the purpose set forth.
- 15 11. In a grinding-machine, the combination with its frame and a grinding-wheel journaled thereon, of a bed supported on the machine in a manner to permit it to be moved toward and away from the grinding- 20 wheel, a reciprocatory work-carrier mounted on said bed, a member coöperating with said carrier and having limited movement relative thereto, means operatively engaging with said member for reciprocating it and 25 said carrier, and means operated by the movement of said member for swinging the bed, for the purpose set forth.
12. In a grinding-machine, the combination with its frame and a grinding-wheel 30 journaled thereon, of a bed supported on the machine in a manner to permit it to be moved toward and away from the grinding-wheel, a reciprocable work-carrier mounted on said bed, a drive-shaft, a movable mem- 35 ber carrying gears operatively connected with said drive-shaft and constructed and arranged to reciprocate said carrier when said member is moved, and means for moving the bed toward and away from the 40 grinding-wheel, for the purpose set forth.
13. In a grinding-machine, the combination with its frame and a grinding-wheel journaled thereon, of a bed supported on the machine in a manner to permit it to be 45 moved toward and away from the grinding-wheel, a reciprocable work-carrier mounted on said bed, a drive-shaft, a movable member carrying gears operatively connected with said drive-shaft and constructed and 50 arranged to reciprocate said carrier when said member is moved, and means actuated by the carrier in its movement for moving the bed toward and away from the grinding-wheel, for the purpose set forth.
- 55 14. In a grinding-machine, the combination with its frame and a grinding-wheel journaled thereon, of a bed supported on the machine in a manner to permit it to be moved toward and away from the grinding- 60 wheel, a reciprocatory work-carrier on said bed, a drive-shaft, a rack operatively connected with said carrier and having limited movement independently thereof, gear- 65 mechanism operatively connected with said drive-shaft and constructed and arranged to

reciprocate said rack and carrier, and means operated by the movement of said rack for swinging said bed, for the purpose set forth.

15. In a grinding-machine, the combination with its frame and a grinding-wheel 70 journaled thereon, of a bed supported on the machine in a manner to permit it to be moved toward and away from the grinding-wheel, a reciprocatory work-carrier on said bed, a drive-shaft, a rack operatively connected with said holder and having limited movement independently thereof, gear- 75 mechanism connected with said drive-shaft and constructed and arranged to reciprocate said rack and carrier, and lever means oper- 80 ated by the movement of said rack for swinging said bed, for the purpose set forth.

16. In a grinding-machine, the combination with its frame and a grinding-wheel journaled thereon, of a bed on the frame 85 movable toward and away from the grinding-wheel, means tending to move said bed in one direction, a work-carrier reciprocable on said bed, a guide adjacent to the bed, a drive-shaft, gear-mechanism operatively connected with said shaft and constructed and arranged to reciprocate said carrier, and 90 means movable with said carrier and engaging with said guide for moving said bed in the opposite direction, for the purpose set 95 forth.

17. In a grinding-machine, the combination with its frame and a grinding-wheel journaled thereon, of a bed on the frame movable toward and away from the grinding-wheel, means tending to move said bed in one direction, a work-carrier reciprocable on said bed, a guide adjacent to said bed, a drive- 100 shaft, a member coöperating with said carrier and having limited movement relative 105 thereto, means operatively connected with said drive-shaft and with said member for reciprocating the latter and the carrier, and means movable with said carrier and bearing against said guide operated by the move- 110 ment of said member for moving the bed in the opposite direction, for the purpose set forth.

18. In a grinding-machine, the combination with its frame and a grinding-wheel 115 journaled thereon, of a bed on the frame movable toward and away from the grinding-wheel, a work-carrier reciprocable on said bed, a member operatively connected with said carrier and having limited movement 120 relative thereto, a guide adjacent to said bed, a lever fulcrumed on said carrier having connection near one end with said member and bearing at its opposite end against said guide, and means operated by said drive-shaft con- 125 structed and arranged to reciprocate said member in opposite directions for moving said member, holder and lever, for the purpose set forth.

19. In a grinding-machine, the combina- 130

tion of its frame and a grinding-wheel journaled thereon, of a bed pivoted near one end to said frame, means engaging with the opposite end of said bed tending to move the 5 bed in one direction, a work-carrier reciprocably mounted on said bed, a rack operatively connected with said carrier and having limited movement relative thereto, a bell-crank lever fulcrumed between its ends on 10 said carrier and connected near one of its ends with an end-portion of said rack and at its opposite end carrying a roller, a guide against which said roller is adapted to constantly bear under the action of said first-named means, a drive-shaft, and means operated by said drive-shaft for moving said rack in opposite directions; for the purpose set forth.

20. In a grinding-machine, the combination with its frame and a grinding-wheel journaled thereon, of a bed supported on the frame in a manner to permit it to be moved toward and away from the grinding-wheel, a work-carrier reciprocably mounted on said 25 bed, a member carried by said carrier and having limited movement relative thereto, a drive-shaft, lever-controlled means for communicating power from said drive-shaft to said member to reciprocate it, means for 30 swinging said bed with relation to the grinding-wheel operated through the movement of said member, means carried by said work-carrier for automatically actuating said lever to reverse the movement of said member when 35 the holder reaches a predetermined point in its forward movement, and means for actuating said lever to disconnect the means controlled thereby from said member when the work-carrier reaches a predetermined point 40 in its return movement.

21. In a grinding-machine, the combination with its frame and a grinding-wheel journaled thereon, of a bed pivotally mounted near one end to said frame, a spring connecting the other end of said bed with the frame and tending to swing said bed relative to the grinding-wheel, a guide adjacent to said bed, a work-carrier reciprocably mounted on said bed, a rack operatively connected 45 with said carrier and having limited movement relative thereto, a bell-crank lever fulcrumed between its ends on said carrier and operatively connected near one of its ends with an end-portion of said rack, and carrying a roller at its opposite end adapted to bear against said guide under the action of said spring, a shaft journaled on said carrier and provided with a pinion at one end engaging said rack, and a second pinion near its 50 opposite end, a drive-shaft carrying a pinion, a movable member carrying gears operatively connected with the pinion on said drive-shaft, said gears rotating in opposite directions and adapted to alternately engage with said 55 second pinion by moving said member, a

lever connected with said member for moving the latter, and means carried by said carrier for alternately engaging with said last-named lever, for the purpose set forth.

22. In a grinding-machine, the combination with its frame and a grinding-wheel journaled thereon, a bed supported on the frame in a manner to adapt it to be moved with relation to the grinding-wheel, a work-carrier reciprocably mounted on said bed, a member 70 carried by said carrier and having limited movement relative thereto, means operated by the movement of said member for shifting said bed during the initial movement of said member, means for reciprocating said member, and means for positively preventing reciprocation of said carrier during the operation of said bed-moving means.

23. In a grinding-machine, the combination with its frame and a grinding-wheel journaled thereon, a bed supported on the frame in a manner to adapt it to be moved with relation to the grinding-wheel, a work-carrier reciprocably mounted on said bed, a member 75 carried by said carrier and having limited movement relative thereto, means operated by the movement of said member for shifting said bed during the initial movement of said member, means for reciprocating said member, and a catch-device constructed and arranged to engage with said bed during the operation of said bed-moving means and be released from engagement therewith upon the conclusion of such movement, for the purpose set forth.

24. In a grinding-machine, the combination with its frame and a grinding-wheel journaled thereon, a bed supported on the machine in a manner to permit it to be moved relative to the grinding-wheel, a work-carrier reciprocably mounted on said bed, a member operatively connected with said carrier and having limited movement relative thereto, means operated by the movement of said member for moving said bed during the initial movement of said member, means for reciprocating said member, a catch-device on said carrier, means on said bed adapted to engage with said catch-device at the limit of movement of said carrier in one direction, whereby the movement of said carrier is prevented during the operation of said bed-moving means, and means operated by the movement of said bed-moving means for disengaging said catch 105 from the bed at the conclusion of the operation of said last-referred to means.

25. In a grinding-machine, the combination with its frame and a grinding-wheel journaled thereon, of a bed supported on the machine in a manner to permit it to be moved toward and away from the grinding-wheel, a work-carrier reciprocably mounted on said bed, a movable member operatively connected with said carrier and having lim- 110

ited movement relative thereto, a guide adjacent to said carrier, a lever pivotally connected with said carrier and connected with said member and bearing at a portion thereof against said guide, means for holding said lever against the guide during the movements of said work-carrier, means for reciprocating said member, a catch-device on said carrier, means on said bed adapted to 10 be engaged by said catch-device at the limit of the movement of said carrier in one direction, and means adapted to be engaged by said lever for releasing said catch from the bed at the conclusion of the movement of 15 said lever relative to said holder, for the purpose set forth.

26. In a grinding-machine, the combination with its frame and a grinding-wheel journaled thereon, of a bed supported on the 20 machine in a manner to permit it to be moved toward and away from the grinding-wheel, a work-carrier reciprocably mounted on said bed, means for reciprocating the carrier, means for moving the bed with relation 25 to the grinding-wheel, a catch-device on the carrier comprising a pivoted catch and a lever operatively engaging it, means on said bed for engaging with said catch, and means operated by said bed-moving means for engaging with said lever, for the purpose set forth.

27. In a grinding-machine, the combination of a plurality of parallel rods of angular

shape in cross-section, a bearing-frame slidably mounted on said rods, a shaft carrying 35 a grinding-wheel journaled in said bearing frame, and means for sliding said frame upon said rods, for the purpose set forth.

28. In a grinding-machine, the combination with its frame, of a plurality of rods of 40 angular shape in cross-section, a bearing-frame slidable on said rods, a shaft journaled in said frame and carrying a grinding-wheel, a rotary shaft having threaded connection with said bearing-frame, and means 45 for rotating said shaft, for the purpose set forth.

29. In a grinding-machine, the combination with its frame, of a plurality of parallel rods of angular shape in cross-section, a 50 bearing-frame slidable on said rods, a shaft journaled in said frame and carrying a grinding-wheel, a rotary shaft having threaded connection at one end with said bearing-frame and provided with a gear at 55 its opposite end, and a second shaft journaled on the machine and provided at one end with a gear meshing with said first-named gear and at its other end with a hand-wheel, for the purpose set forth.

WILLIAM J. BASTIAN.
FRANK GRANITZ.
